UNITED STATES PATENT OFFICE.

MAHLON E. LAYNE, OF MEMPHIS, TENNESSEE.

APPARATUS FOR SEPARATING FLUID IN WELLS.

1,311,169.

Specification of Letters Patent. Patented July 29, 1919.

Application filed September 26, 1917. Serial No. 193,746.

To all whom it may concern:

Be it known that I, MAHLON E. LAYNE, a citizen of the United States, residing at Memphis, in the county of Shelby and State 5 of Tennessee, have invented certain new and useful Improvements in Apparatus for Separating Fluid in Wells, of which the following is a specification.

This invention relates to apparatus for 10 separating the fluid in wells, either oil, gas, or water, from the formation in which it is found. It has for its primary object the provision of apparatus which will cause the fluid to separate from or leave the formation 15 at a point in advance of the point of entry into the fluid withdrawing means and without the use of some one of the usual and well known forms of mechanical strain- 20 ers so commonly employed at present, such, for example, as a perforated supporting casing wrapped with a helix of screening wire. It involves, in place of such mechanical straining, the use of a natural filtering or 25 separating process, as will more clearly appear hereinafter. Further and more specific ob- 30 jects of the invention are the provision of apparatus for the purpose described which shall be composed of two members independ- 35 ently formed and afterward put together in a most simple manner; and the manufac- 40 ture of such apparatus in sections to be bolted, riveted or welded together to form a substantially continuous construction, all of 45 which will clearly appear in connection with 50 the description of the accompanying draw- 55 ings forming a part of this application.

Figure 1 is a longitudinal section in perspective of a portion of a construction em- 60 bodying my invention; Fig. 2 is a side ele- 65 vation thereof; and Fig. 3 illustrates a 70 modification.

By referring to the figures, it will be seen 75 that the invention consists, generally speak- 80 ing, of two apertured members placed one 85 within the other and riveted together, the 90 apertures of one or of both of the members 95 being so formed and the members being so 100 placed together as to create a short channel 105 or passageway from one opening to the 110 other. The apertures referred to are prefer- 115 ably formed by cutting a plurality of slits 120 in the cylinders and pushing or crowding the 125 metal inwardly or outwardly in any preferred 130 manner. The metal pushed out forms a hood 135 with an opening at its edge. All of the hoods 140 on the outer member are formed to project

outwardly with the openings 10 all facing downwardly and, if it be desired to have the hooded openings in both members, all of the hoods on the inside member are formed to project inwardly with the openings 12 facing upwardly, as shown. The two members readily telescope for purposes of assembly. The hoods are aligned and are so positioned as to bring the opening under 145 one hood opposite the base of the other hood. This forms a channel or passageway 11 between the two openings. The opening 10 forms the inlet to this channel and the opening 12 forms its outlet to the interior of 150 the tube. It should here be noted that the point of fluid separation adjacent the opening 10 is below the point of fluid entry into the tube at the opening 12. The flow of 155 fluid through the channel 11 is upwardly. The fluid bearing formation (not shown) 160 in which the apparatus is placed fills in adjacent the opening 10 but is prevented from filling the channel 11 and is relieved of 165 excessive pressure by the projecting hood 170. The protection thus afforded the formation 175 adjacent the opening 10 allows its particles to assume a certain looseness, such for example, as would be present in a filter composed of sand and gravel, from which the 180 water or other fluid can readily separate. In this manner, it will be seen, separation is accomplished at a point in advance of the 185 final point of entry into the interior of the tube, and because the fluid must pass upwardly through the channel 11 before it enters the tube, the particles of the formation 190 are left behind and are not carried into the interior.

Also, because there is a plurality of these 195 inclined entry passages provided, as shown, the rate of fluid flow through each, and at the point of separation, is maintained at a minimum. By thus reducing the velocity of the flow at the point of separation, the fluid 200 does not entrain and hold in suspension particles of the formation to be carried into the interior of the well. These separation points are, in effect, what may be termed small natural springs. The water seeps or 205 percolates through the loose formation adjacent the openings 10, fills the channel 11 and then enters the tube through the opening 12.

In Fig. 3 I have illustrated a modification. In this construction the hooded openings are provided only in the outside member 8, the

openings in the inside member 7 being merely rectangular slots 15 arranged to come opposite the bases of the hoods 9 in the outer member. This form of construction has the advantage of presenting a smooth, unbroken inner wall surface, which permits of greater ease in the passing of bailers, drills or other tools up and down in the well while retaining at the same time the advantages of an inclined channel through which the fluid must flow upwardly to the interior of the well pipe.

The two members are fastened together in any preferred manner, rivets 13 being used in this case, and one member being arranged to project beyond the other, as shown. This provides a most convenient means for coupling sections together, the projecting portion at the end of one section telescoping with the projecting portion at the opposite end of another section, the joint being made secure by means of rivets, or in any other preferred manner. It will, of course, be understood that at the opposite end (not shown) of a section of tubing the outside member is the one which projects, which makes possible the telescopic engagement described.

It will be seen that the construction disclosed is most simple to manufacture, assemble, and install. It permits the use of that class of metal known as boiler steel metal which is more generally available than other classes and at a lower price. The construction is most effective and accomplishes the separation of the fluid without the use of a mechanical screening element.

I claim:

1. In well apparatus, a tubular fluid collecting member formed of two casings, the inner casing having formed therein a plurality of displaced portions the upper terminals of which open into the collecting member, and the outer casing having a plurality of displaced portions the lower terminals of which open exteriorly of the collecting member, the said displaced portions being arranged in juxtaposition so as to constitute inclined inlet channels.

2. In well apparatus, a tubular fluid col-

lecting member formed of an inner casing and an outer casing, apertures in both casings, and offset portions in the outer casing providing upwardly inclined passageways connecting the apertures of one wall to the 55 apertures of the other.

3. In separators for wells and the like, an inner perforated casing, and downwardly and outwardly extending protector members on the outside of the casing overhanging 60 the apertures therein, said protector members being larger than the apertures and extending beyond the edges of the apertures both vertically and horizontally.

4. In separators for wells and the like, an inner perforated casing, and nose shaped protectors on the outside of the casing over its apertures, said protectors joining with the casing above and at the sides of the apertures and extending below the apertures, forming openings only at their lower ends through which fluid must flow upwardly to reach the apertures.

5. In separators for wells and the like, an inner perforated casing, an outer sheathing 75 around the perforated casing, said sheathing having openings struck therethrough in register with the casing apertures, the sheathing openings being larger than the casing apertures and extending beyond the sides 80 and lower edge of the casing apertures, and the metal struck out of the sheathing to form the apertures forming downwardly and outwardly extending protector members which overhang the casing apertures.

6. In separators for wells and the like, an inner perforated casing, an outer sheathing around the perforated casing, said sheathing having openings struck therethrough in register with the casing apertures, the 90 sheathing openings being larger than the casing apertures and extending beyond the sides and lower edge of the casing apertures, and the metal struck out of the sheathing to form the apertures forming nose-shaped protectors with openings at their lower ends only.

In testimony whereof I have hereunto signed my name,

MAHLON E. LAYNE.
